UNITED STATES PATENT OFFICE.

DANIEL M. CALHOUN, OF CLARKS, LOUISIANA.

AEROPLANE.

1,087,724.

Specification of Letters Patent. Patented Feb. 17, 1914.

Application filed March 3, 1913. Serial No. 751,756.

To all whom it may concern:

Be it known that I, DANIEL M. CALHOUN, a citizen of the United States, and a resident of Clarks, in the parish of Caldwell and State of Louisiana, have invented a new and Improved Aeroplane, of which the following is a full, clear, and exact description.

My invention is applicable to monoplanes or biplanes, and it relates particularly to a form of plane in which the front portion is essentially rigid and non-vibratory, while the rear portion is vibratory and has connected therewith a vibrator adapted to impart short and rapid vibrations in a vertical plane. The vibratory rear portion of the plane is continuous with the rigid front portion, so that the upper and lower surfaces of the complete plane are continuous, while at the same time the rear portion, which is flexible, constitutes in effect, a fishtail propeller. The plane preferably is curved, the curve decreasing toward the rear. The vibrating of the rear portion of the plane may exert a propelling force auxiliary to that of known propellers with which the aeroplane may be equipped, or may be utilized alone as a propelling means.

The distinguishing features of my invention, and the important structural elements characterizing the preferred practical embodiments which are illustrated as examples, will be more particularly explained in the specific description hereinafter to be given.

Reference is to be had to the accompanying drawings forming a part of this specification, in which similar characters of reference indicate corresponding parts in all the views.

Figure 1 is a partly sectional side elevation of a biplane embodying my invention; Fig. 2 is a diagrammatic rear view of the vibrator devices; Fig. 3 is a plan view of the plane and the vibrator devices; Fig. 4 is an enlarged detail vertical section of a portion of the plane on the line 4—4 of Fig. 3; Fig. 5 is a detail transverse sectional elevation of the plane and a portion of the vibrator devices; Fig. 6 is a side view on an enlarged scale of one of the arms attached to the plane, and with which the vibrator means are connected; Fig. 7 is a rear edge view showing a pair of arms such as shown in Fig. 6, and other details to be hereinafter referred to; Fig. 8 is a detail plan view of a lateral brace bar employed between

the ribs of the plane; Fig. 9 is a sectional side elevation of a monoplane embodying my invention; Fig. 10 is an enlarged, detail sectional side elevation of the actuating devices for vibrating the plane; and Fig. 11 is an enlarged longitudinal vertical section of the plane.

In constructing a biplane in accordance with my invention, the general type may be of any approved design. I provide upper and lower planes 10, sustained at the front by posts 11, and at an intermediate point by posts 12. Any suitable motor 13 may be mounted on the machine, and rearwardly extending frame bars 14 may be employed to carry any approved arrangement of steering rudder (not shown). At the front of the machine there extend in front of the plane, forwardly ranging frame members 16, the frames converging and in practice, carrying at their point of intersection a horizontal elevating rudder (not shown). I have indicated in the monoplane (Fig. 9) an elevating rudder 21. The machine is provided with a lever 17, connected by a rod 18 with the usual steering rudder, and is equipped with the lever 19 having a rod 20, which in practice, will lead to the elevating rudder in front, these parts being of any approved form and arrangement.

My improved planes are made up of parallel ribs 22 ranging fore and aft, the several ribs being connected by forward transverse bars 23 and transverse bars 24 on a line rearward of the front edge. The several bars 23 are covered at the top and bottom by a sheet 25 of canvas or equivalent material, the upper and lower stretches of which are suitably united by rows of stitching 26, to maintain the canvas taut. The ribs 22 are of gradually reduced thickness toward the rear ends, and in order to support the upper layer of the canvas flush with the upper surfaces of the cross bars 23, 24, I employ a strip 27, of cork or its equivalent, on the upper surface of each rib in the rear of the back cross bar 24 and taping from said cross bar rearwardly. Between the front and rear cross bars an additional strip 27a is secured, said strips 27, 27a having their upper surfaces flush with the cross bars.

The posts 11, 12, and the cross bars 23, 24, maintain the front portions of the ribs substantially rigid and non-vibratory. The rear end of each rib at the rear of the back cross

- bar 24 is free and unbraced vertically, in order that the rear ends of the ribs may be capable of receiving rapid, short vibrations in the vertical plane by vibrator devices connected at points 28 (Fig. 11) between the rear edge and the transverse bar 24. Adjacent to the point of connection 28 for the vibrator means, the rib is preferably given increased thickness, as at 29.
10. Rocker arms 30 are rigidly secured to certain of the ribs 22, preferably between the upper and lower ends of the said arms, that the latter may be suitably trussed, as herein-after explained. The arms 30 are approximately perpendicular to the ribs, and connected with said arms by wrist pins 31 or the like, are connecting rods 32, which have connection also with a crank shaft 33 having suitable bearings in the frame members.
15. Preferably, rearwardly converging diagonal frame members 34, 35, are provided to support the crank shaft 33. The shaft may be driven from the engine 13, by any suitable means, such for instance as a belt 36, indicated in dotted lines in Fig. 1, running over a pulley 37 on a counter-shaft 38 driven from the drive shaft 38^a. The rearwardly converging bars 34, 35, are connected suitably as at 34^a, 35^a, with the front post 11 and with the rear post 12, as at 34^b, 35^b, and crossed braces in the form of wires or rods 39, 40, are provided between the mentioned points of connection.
20. The driven shaft 33 which communicates vibratory movements to the plane has a plurality of cranks 41, and the cranks and the arms 30 and connecting rods 32 are provided at intervals between the ribs 22. To steady the crank shaft and balance the same, a balance wheel 42 is provided, and in order that the latter may be driven at high speed, it is mounted on a counter shaft 43 having a spur pinion 44 in mesh with a spur gear 45 on the crank shaft 33. Balance wheels 42 are provided in suitable number desirably to equal in number the cranks 41.
25. To brace the plane laterally and resist lateral strain on the ribs 22, the several ribs near their rear ends are braced by interposed transverse bars 46, made up in short sections to fit between adjacent bars 22. Any suitable joint members 47 are provided; these are shown conventionally in Figs. 3 and 5 and one form is illustrated in detail in Fig. 7. The coupling members in the illustrated form have loops or openings 48, to receive the ribs 22, and lateral arms 49 extend from the loops in opposite directions to receive the ends 50 of the brace bar sections 46. The 30 ends of certain of the brace bar sections may have tenons 51 which enter mortises 30^b in the arms 30. The provision of the brace bar sections 46 serves to unite and brace the, flexible rear ends of the ribs 22, so that a vibratory motion imparted to certain of the

ribs will cause all the ribs to vibrate in unison.

The arms 30 are trussed by truss wires 52 the ends of which are connected as at 53 with the joint members 47, or other elements 70 along the line of the brace bars 46, whereby as will be seen from Fig. 5 the arms 30 constitute struts. Auxiliary struts 54 are provided at each side of the arms 30, and of less height, so that the truss wires 52 and strut elements 30, 54, form a diamond-shaped structure. Additional guy wires 52^a extend over the ends of the arms 30 diagonally to the adjacent joint members 47, as indicated clearly in Fig. 5. The described construction contributes to the transverse bracing of the flexible portions of the ribs to cause all to vibrate in unison.

In Fig. 9 is illustrated a monoplane in which an engine 13^a is mounted on any suitable body 13^b. The structure includes a post 12^a to which the plane 10^a is suitably secured adjacent to the rear transverse bar 24^a of the plane, and converging diagonal frame elements 12^b extend from the ends of 90 the posts 12^a to a suitable connection with the front cross bar 23^a of the plane. The elevating rudder 21 is mounted in the converging terminals of forwardly extending bars 16^a. The crank shaft 33^a actuates the 95 connecting rod 32^a, which is connected also at 31^a with the rocker arms 30^a, which are similar to the rocker arms 30. The plane includes the strips 27 and 27^a applied to the ribs 22^a, as described in connection with the 100 biplane. The crank shaft 33^a is provided with a spur gear 45^a in mesh with a spur pinion 44^a on a counter-shaft 43^a, the latter shaft having also a fly wheel 42^a.

It is to be understood that the crank shaft 105 33 is driven at high speed and will thus, through the connecting rod 32 and rocker arms 30, cause a very rapid vibration of the rear portion of the plane, the vibrations being short. It will be obvious that the vibrating portion of the plane will result in a propelling action somewhat after the manner of a fish-tail propeller. The air currents at the rear edge of the plane and behind the plane will be modified, my design being to lessen 115 the drag on the plane as with the ordinary non-vibrating constructions. In practice, the aeroplane may be provided with any approved propelling means. The vibrating of the plane, I find, also has a lifting 120 effect.

The described construction affords a practical means for carrying my invention into effect, and I would state in conclusion, that I do not limit myself strictly to the mechanical details herein illustrated, since manifestly the same can be considerably varied without departing from the spirit of the invention.

Having thus described my invention, I 130

claim as new, and desire to secure by Letters Patent:

1. An aeroplane, comprising a frame, a plane mounted therein and having its front portion held substantially rigid, the rear portion of the plane being flexible, and high speed vibrator devices connected with the flexible portion of the plane and having a limited movement to impart short and very rapid vibrations to the said rear portion of the plane.
2. An aeroplane, comprising a plane having a vibratory portion extending from its rear edge forwardly, and extending laterally the full width of the plane considered transversely to the longitudinal axis of the aeroplane, a frame having members sustaining the front portion of the plane rigid and non-vibratory, and a high speed vibrator means connected with the plane at the rear portions and adapted to impart to the latter throughout its full width, short, rapid vibrations in the vertical plane.
3. In an aeroplane, a plane having its rear portion flexible and adapted to vibrate relatively to the front portion and in a vertical plane, the said vibratory rear portion being continuous with the non-vibratory front portion of the plane, a vibrator means connected with said vibratory portion, and means for actuating the said vibrator means.
4. In an aeroplane, a plane made of a rigid, non-vibratory front portion, and a rear flexible portion constituting a substantial proportion of the plane forming a continuation of the front portion, the said flexible rear portion being adapted to vibrate to constitute a fishtail propeller; in combination with high speed actuating means operatively connected with the said flexible portion, for vibrating the same.
5. In an aeroplane, a plane comprising a plurality of ribs ranging fore and aft, sheet material carried by said ribs, posts sustaining the front portions of the ribs, cross bars uniting said front portions of the ribs, the said front portions of the ribs being rigid, the rear portions of the ribs in the rear of the cross bars being free and flexible, transverse members uniting the flexible portions of the ribs, and high speed vibrator devices for imparting rapid and short vibrations to the said rear portions.
6. In an aeroplane, a curved plane, the depth of the curve decreasing toward the rear end, the front portion of the plane being rigid and the rear portion being flexible, and means to impart rapid vibrations to the flexible rear portion of the plane throughout the full width thereof considered transversely to the axis of the aeroplane.
7. In an aeroplane, a curved plane comprising a series of spaced ribs extending fore and aft, sheet material carried by the ribs, means for sustaining the front portions of the ribs rigid and non-vibratory, the rear portions of the ribs being free and flexible, means for uniting the rear portions of the ribs transversely, and means for imparting rapid vibrations to the rear portions of the ribs in a vertical plane.
8. In an aeroplane, a plane comprising ribs extending fore and aft and spaced from each other transversely, a transverse bar uniting said ribs at the front, a second transverse bar uniting said ribs rearward of the front bar and at the top of the said ribs, strips applied to the ribs at the top, the upper surface of the said strips being substantially flush with the cross bars, the rear ends of the said ribs tapering, a sheet material applied to the ribs, transverse bar sections interposed between the tapered rear portions of the ribs on a line forward of the rear of the ribs, a rocker arm connected with said ribs adjacent to the bar sections, and high speed vibrator means connected with said rocker arms.
9. In an aeroplane, a plane comprising ribs extending fore and aft and spaced apart transversely, the rear ends of the ribs being flexible, means for uniting said ribs at their forward portions, means rigidly sustaining said forward portions, means uniting the rear flexible portions of the ribs to vibrate in unison, and high speed vibrator means connected with the plane at intervals at the flexible portions of the ribs, to impart rapid vibrations thereto in the vertical plane.
10. In an aeroplane, a frame comprising a post, a plane having ribs extending fore and aft and connected with said post, the rear portions of the ribs being flexible, a crank shaft, rocker arms rigidly secured to certain of the ribs, and connecting rods connected with the said rocker arms and with the crank shaft.
11. In an aeroplane, a plane comprising ribs extending fore and aft and spaced apart transversely, means sustaining the front portions of the said ribs rigid, the rear ends of the ribs being flexible to vibrate in a vertical plane, sheet material carried by said ribs and extending continuously over the rigid and flexible portions thereof, transverse connections between the several ribs at their flexible portions to brace the said flexible portions and cause the same to vibrate in unison, and high speed vibrator means connected with the flexible portions of the ribs to vibrate the same in a vertical plane.
12. In an aeroplane, a plane comprising ribs extending fore and aft and spaced apart transversely, sheet material carried by said ribs, the rear portions of the ribs being flexible, means for maintaining the front portions of the ribs rigid and non-vibratory, connecting members uniting the several ribs.

at the flexible portions, rocker arms rigidly secured to certain of the ribs at the flexible portions and extending above and below the same, truss members extending transversely 5 of the rocker arms and ribs around the tops and bottoms of the rocker arms, and connected at their ends with the plane at points distant from the sides of the rocker arms, a connecting rod connected with the rocker 10 arms, a crank shaft connected with said

connecting rod, and means for imparting high speed to the said crank shaft.

In testimony whereof I have signed my name to this specification in the presence of two subscribing witnesses.

DANIEL M. CALHOUN.
